GEORGE SCHMITT, OF NEW YORK, N. Y.

EXTENSION-TABLE.

SPECIFICATION forming part of Letters Patent No. 416,424, dated December 3, 1889.

Application filed April 25, 1889. Serial No. 308,569. (No model.)

To all whom it may concern:

Be it known that I, GEORGE SCHMITT, of the city, county, and State of New York, have invented a new and Improved Extension-Table, of which the following is a full, clear, and exact description.

My invention relates to extensible tables adapted more especially for dining-rooms, but applicable for use where almost any table would be serviceable; and the invention has for its object to provide a simple, substantial, and readily-adjustable table of this character.

The invention consists in certain novel features of construction and combinations of parts of the extension-table, all as hereinafter described and claimed.

Reference is to be had to the accompanying drawings, forming a part of this specification, in which similar letters of reference indicate corresponding parts in all the figures.

Figure 1 is a central longitudinal sectional elevation of my improved extension-table, taken on the line $x-x$ in Fig. 3. Fig. 2 is an inverted plan view thereof with parts in horizontal section on the line $y-y$ in Fig. 3 and with other parts broken away. Fig. 3 is a vertical transverse section taken through one end portion or frame of the table and on the line $z-z$ in Fig. 1, and Figs. 4 and 5 are detail bottom plan and sectional side views of a latch device used to lock the extensible end sections of the table to the main top part thereof.

The table shown in the drawings is made with two opposite end frames or box-like parts A A, which are each supported on legs B, four centrally-disposed legs being preferred on each end frame of a heavy table. As both frames A A are made substantially alike, a detailed description of one frame will answer for both of them, as follows: The end frames are each made with an end wall a and two opposite side walls $a' a'$, secured thereto and braced by a cross-bar a^2 , which is fixed comparatively near the end wall a and about at the point from which the slatted or flexible portion of the table-top rolls out of and into the frame, as hereinafter more fully explained. Longitudinally-ranging boards or pieces $a^3 a^3$ are fixed at their outer ends to the lower edge of the end wall a and at their

inner ends are supported by metal braces a^4 , fixed to them and to upper stationary guide-plates D D, which, with lower stationary guide-plates E E, are fixed to the opposite side walls $a' a'$ of the frame. These pieces a^3 give substantial support to the frame A on the legs B, which are fitted to them and suitably fastened.

The metal braces a^4 are shown in full lines in Fig. 1 and their positions are indicated in dotted lines in Fig. 3 of the drawings.

To the cross-bar a^2 of the frame A are fixed the outer ends of a pair of bars F F, which slide by suitable tongue-and-groove joints in guide-bars f, fixed, preferably, by screws to the under side of the main unbroken top board or plate G of the table and which, with the two end pieces H H of both frames, form the complete top of the table when it is in fully-contracted condition.

The end board or piece H of the table-top is hung by hinges h to the top of the end wall a of the frame A, and its free inner edge portion h' , which is beveled upward and outward at the under side, acts as a latch or stop between the top plate G and the first narrow strip or slat of the adjacent rolling or flexible section of the table-top, or between any two strips or slats thereof, to lock the table-top at any desired degree of extensibility, as hereinafter more fully explained.

Under the hinged top piece H and in a recess in the end wall a of the frame A is placed a suitable spring I, preferably of spiral form, and which raises the piece H on its hinges when it is unlatched. The catch for the piece H consists of a headed pin J, fixed to its under side and adapted to be engaged or overlocked by the hook-head of a spring-latch K, which is fastened at its lower end to the end wall a of the frame.

To the latch K is connected a pin k, which extends through the frame-wall a and may be pushed in to throw the latch back and release the catch J and allow the spring I to automatically raise the top piece H on its hinges to allow lengthwise readjustment of the table, and by simply lowering the piece H its catch J will automatically engage the latch K to hold said top piece down level with the main top plate G or one or more of the series of slats L, which may then constitute the exten-

sible and contractible portion of the table-top.

The main unbroken top board or plate G of the table is as long as the combined lengths of the two end frames A A from the inner edges of their hinged or movable end pieces H H to the inner ends of said frames, so that when the table is fully contracted the opposite ends of the top piece G will make a close joint with the inner edges of the top parts H H, while the two end frames will make a close joint at their abutting inner ends.

When the table is constructed to be extensible at both ends, as shown in the drawings, a web M, of canvas, leather, or any other suitable flexible material, which is secured by glue or other otherwise to the under side of the main top G, will be extended endwise each way therefrom for any length required to allow a series of slats L of any desired number to be glued or otherwise fastened at their lower faces only to the web at each end of the main top G.

The hereinbefore-mentioned guide-plates D E are connected in pairs one above the other to the opposite sides a' a' of each end frame A and to the cross-bar a² thereof, as most clearly shown in Figs. 2 and 3 of the drawings.

The guide-plates D are each provided at its upper face with a longitudinally-ranging dovetail rail d, and the guide-plates E, which are located below the guides D, have rounded opposite ends and are provided all around, or at top, bottom, and both ends, with a continuous dovetail rail e. The dovetail guide-rails d e at the same side of the table lie in the same vertical plane.

The main top board or plate G and all the slats L of the rolling top portion of the table are provided at their under sides and near each side of the table with undercut or dovetail grooves m, into which the dovetail guide-rails d e are adapted to pass loosely. The entire table-top G L is thus free to be shifted endwise of the table, the main top G sliding only on the rails d of the upper guide-pieces D, while the rolling strip portions L of the top slide by their dovetail grooves on the dovetail rails d of the upper guides D, and also upon and around the continuous dovetail rails e of the lower guides E of each end frame A of the table.

To the under side and lengthwise center of the main top G is fixed a transversely-ranging block g. (See Figs. 1 and 2 of the drawings.) I prefer to fix to this block an intermediate leg B', which extends to the floor as a support to the table-top portion G, and is provided with ornamental lateral projections b' b', extending from opposite sides of it, and which, when the table is fully closed, abut the inner legs B of the two end sections of the table and extend in horizontal alignment with the stay-bars or frame-work b between the two pairs of end legs of each end frame A of the table.

Each of the end sections A of the table is

locked to the center block g when the table is fully closed by means of a latch device which engages a catch-plate fixed to the block. This special latch device is shown in detail in Figs. 4 and 5 of the drawings, and consists of a latch-bar N, which has a hook-head n and is pivoted at n' to swing vertically on an arm O, which is itself preferably pivoted to swing horizontally on a pin or screw o, which is fixed in a metal plate P, secured to the under face and inner end of one of the boards or pieces a³ of the end frame A of the table. Stop-pins p p' on the plate P limit the turning movement of the arm O and latch N on the pin o, and a spring R, held to the plate P and acting on the back end of the arm O, holds it to whichever stop-pin p or p' it may be adjusted. When the arm is swung over to the pin p, it projects from the frame-piece a³, so as to hold the latch N in position to engage the downwardly-bent end or flange s of the catch-plate S, whereupon a screw T, which is threaded into the outer end of the arm, is turned to lift the outer end or head n of the latch and cause it to press on the catch-plate flange s, and thereby draw the parts a³ g firmly together and hold the end frame A securely to the block g, and consequently to the main top G, to which this block is fixed. By turning back or lowering the screw T the latch N will fall or will be carried down clear of the catch-plate by a spring U, which is held to the latch-pivot and bears by opposite ends on the latch and arm N O. When the latch is thus disengaged from the catch-plate, the arm O will be swung around to stop against the pin p' on the plate P, where it will be held by the spring R within the end of the piece a³ and out of danger of being struck and damaged by the catch-plate S the next time the closing end frame strikes the block g on the main top plate of the table. By making the latch-arm O to swing horizontally and fitting the vertically-movable screw T in it so as to bear up against the latch-bar N, as above described, it is obvious that the screw need be lowered but a trifle to allow the latch-head to swing around behind the flange s of the catch-plate as the arm O is swung around on its pin o; hence but a few turns of the screw are required to either loosen or securely lock the closed joint between the block g and either of the end portions A B of the table. The latches N O T U are held one to the right-hand piece a³ of one end frame A of the table and the other to the left-hand piece a³ of the other end frame of the table.

The operations of extending and contracting the table are very simple and are easily performed. When the table is wholly closed, the inner edges or portions h' of the two hinged end top plates H H will be held by their latches J K down snugly between the adjacent end of the main top G and the first slats L of the two rolling series of slats, as shown at the left-hand end of Fig. 1 of the

drawings, and both latches N N will be locked to the catch-plates S S of both end frames A A, and the table in this contracted condition or adjustment can be grasped and moved or 5 rolled about without danger of accidental extension of it so long as the latch-pins k and latch-screws T remain undisturbed. To prevent accidental operation of the latches K, I may keep the outer ends of their push-pins k 10 flush with or back of the face of the ends of the flanges A, as shown at the right-hand end of Fig. 1 of the drawings. It will be noticed that when the top portions G H are in contact and the end parts H are latched down all the 15 slats L held to the flexible web M will be within the end frames A, and for the most part will be rolled around the lower guides E at opposite sides of the table, it being understood that the slats are held to said 20 guides as they curl or curve around them by their dovetail slots, which fit the dovetail rails e of the slides. Should the table be fully closed or contracted and should it be desired to extend it at one end only, the pin k at that 25 end will be pushed in, which will disengage the latch K from the catch J on the hinged top plate H, which will be instantly raised by the spring I, as indicated by the dotted lines at the right-hand end of Fig. 1 of the drawings, 30 and after the screw T of the latch N at that end of the table is slackened and the arm O is swung around on its pivot o to the stop p' the end frame A will be drawn outward, and while it moves by its inner slides F on the 35 guide-rails f, fixed to the main top G, the slats L will be drawn outward and upward, from the dovetail rail e of the lower guides E, and their dovetail bottom grooves will, as they rise to the level of the main top G, engage 40 the dovetail rails d of the upper guides D to hold the slats down to a true level to form part of a substantial top to the table. Should the table not be long enough when extended at one end, it may in like manner be extended 45 at both ends. It is obvious that the table may be extended at one or both ends to any desired degree which will allow the latch end h' of the end top piece H to be lowered and latched between any two of the slats L, which 50 will lock the table securely at the required adjustment. To contract the table again, the pin k at the extended end will be pushed in to disengage the latch K from the catch J on the top piece H, which then will rise, and 55 after the extended end of the table is pushed in the latch-arm O will be swung around to swing its latch N around behind the catch S on the center block g, and the screw T will then be turned to force the latch-head to the 60 catch and bind or lock the lately-closed section fast to the rest of the table, and the top piece H will then be swung down and secured by the latch K. The table may be made with extensible slat top sections L at one end 65 only of it and connected by a flexible web to a fixed main top plate which will extend

clear to the other end of the table, as will readily be understood.

Having thus described my invention, what I claim as new, and desire to secure by Letters Patent, is—

1. An extension-table constructed with an end frame, a main top plate thereon, a flexible web held to said plate, a series of slats attached to said web and forming a flexible 75 rolling top for the table, and an end top piece hinged to the frame and adapted to lock at its inner edge between the main top plate and the adjacent slat of the flexible top or between any two slats of said top, substantially as herein set forth.

2. An extension-table constructed with an end frame, a main top plate thereon, a flexible web held to said plate, a series of slats attached to said web and forming a flexible 85 rolling top for the table, an end top piece hinged to the frame and adapted to lock upon and between the flexible top slats, and a detent holding the hinged end top piece in locking position, substantially as herein set forth. 90

3. An extension-table constructed with an end frame, a main top plate thereon, a flexible web held to said plate, a series of slats attached to said web and forming a flexible rolling top for the table, an end top piece hinged to the frame and adapted to lock at its inner edge onto and between the flexible top slats, and a spring raising the hinged end top piece when the detent is disengaged, substantially as herein set forth. 95

100

4. In an extension-table, the combination, with an end frame provided with upper guides D d and lower rounded guides E e, of a main top plate G, fitted to the guides D d, a web M, connected to said top G, a series of strips L, 105 held to the web and adapted to the guides D d and E e, a hinged end top piece H, having an inner edge h', adapted to lock with the parts G L, and a latch-detent for the lowered piece H, substantially as herein set forth. 110

5. In an extension-table, the combination, with an end frame, a main top plate, a series of strips connected to the plate and forming a flexible top for the table, an end top piece H, hinged to the frame and having an inner 115 edge h', adapted to lock with the main top plate and top strips, a catch J on said piece H, a latch K, held to the frame and adapted to engage the catch when the piece H is lowered, and a push-pin k at the end of the frame 120 and adapted to disengage the latch and catch, substantially as herein set forth.

6. The combination, in an extension-table, of two end frames provided with extension-slides F and table-top guides D d E e, a main 125 top plate G, fitted to the guides D d and having slides f, to which those F of the end frames are adapted, a flexible web or connection fastened to and extending from both ends of said plate G, a series of slats L, forming a 130 rolling top section and attached to the flexible connection at each end of the plate G and

fitted to the guides D d and E e, and adapted to roll within the end frames, a top piece H, hinged to the outer end of each end frame and adapted to lock onto the slats L, and a 5 latch or detent holding each end piece H down to said slats, substantially as described, for the purposes set forth.

7. In an extension-table, the combination, with the main top plate of the table and an 10 extensible frame movable relatively to said top, of a catch on the top, an arm on the end frame, a latch pivoted to said arm for vertical movement, and a screw fitted in the arm and adapted to press the latch to the catch, 15 substantially as herein set forth.

8. In an extension-table, the combination, with the main top plate of the table and an extensible frame movable relatively to said 20 top, of a catch on the top, an arm pivoted on the end frame for horizontal movement, a latch pivoted to said arm for vertical movement, and a screw fitted in the arm and adapted to press the latch to the catch, substantially as described, for the purposes set 25 forth.

9. In an extension-table, the combination, with an end frame and a main top plate G, of a block g, fixed to the plate G and provided

with a catch and a latch held to the end frame and consisting of an arm, a latch-bar N n, 30 pivoted thereto for vertical movement, and a screw T, threaded into the arm and adapted to the latch, substantially as herein set forth.

10. In an extension-table, the combination, with an end frame and a main top plate G, of 35 a block g, fixed to the plate G and provided with a catch S s and a latch device held to the end frame and consisting of an arm O, pivoted to the end frame for horizontal movement, a latch N n, pivoted to the arm for vertical movement, and a screw T, threaded into the arm and adapted to the latch, substantially as herein set forth.

11. In an extension-table, the combination, with its end frame and a top plate provided 45 with a block g, of a catch S s on the block, an arm O, pivoted to the end frame, a spring R, acting on the arm, stops p p' on the end frame for the arm, a latch N, pivoted to the arm, and a screw T in the arm, adapted to press the 50 latch N to the catch S, substantially as herein set forth.

GEORGE SCHMITT.
